BARBECUE

Peter D. Donlon, 149 Beechwood Drive,
Oakland, Calif. 94618

Filed Feb. 24, 1967, Ser. No. 5,942

Term of patent 14 years

(Cl. D81—10)

FIG. 1

FIG. 2

FIG. 3

FIGURE 1 is a perspective view of my new design with the grill in operative position as a barbecue;

FIGURE 2 is a similar perspective view with the grill hinged upwardly for use as a campfire;

I claim:

The ornamental design for a barbecue, as shown and described.
